[57] CLAIM

The ornamental design for a control buckle for positioning and retaining a diver's weight, as shown and described.

DESCRIPTION

FIG. 1 is a perspective view on a reduced scale of a control buckle for positioning and retaining a diver's weight showing my new design, a belt fragment and weight being shown therein in broken lines for illustrative purposes only;

FIG. 2 is a perspective view of the control buckle;

FIG. 3 is a top plan view thereof;

FIG. 4 is a side elevation thereof, the side opposite being identical thereto;

FIG. 5 is a bottom plan view thereof;

FIG. 6 is an end view thereof, the end opposite being identical thereto; and,

FIG. 7 is a vertical cross section taken substantially along line 7—7 of FIG. 3.

FIG. 1**FIG. 2****FIG. 3****FIG. 4****FIG. 5****FIG. 6****FIG. 7**
